UNITED STATES PATENT OFFICE.

OTTO UNZICKER, OF CHICAGO, ILLINOIS, ASSIGNOR TO ADOLPH SHOENINGER, OF SAME PLACE.

VELOCIPED.

SPECIFICATION forming part of Letters Patent No. 242,490, dated June 7, 1881.

Application filed February 21, 1881. (No model.)

To all whom it may concern:

Be it known that I, OTTO UNZICKER, of Chicago, in the county of Cook and State of Illinois, have invented a certain new and useful Improvement in Velocipedes, of which the following is a specification.

The object I have in view is to produce a spring-seat for velocipedes having two or more wheels, which seat will be simple and cheap in construction, can be readily secured in place, and will be exceedingly strong and durable in use.

My invention therein consists in the peculiar device employed by me for this purpose, as fully hereinafter explained, and pointed out by the claims.

In the accompanying drawings, forming a part hereof, Figure 1 is a side elevation of the head of the velocipede, the fork-standards and back bars being broken off; Fig. 2, a vertical section of the parts, taken through the seat and its arm; Fig. 3, a cross-section on line 3 3, looking toward the fork-standards; and Fig. 4, a cross-section through the seat-arm and its holding-bolt, the seat and back bars not being shown.

Like letters denote corresponding parts in all four figures.

The round fork-standards A are secured together at their upper ends by the cast-metal head B, through the side arms of which bolts pass to plates a on the forward sides of the standards, such plates forming, with the arms of the head, sockets for receiving the standards. The cast-metal head B rises above the standards A, and has the handle C secured to its upper end.

The round back bars, D, at their upper ends, are secured between socket-plates E E'. The lower socket-plate, E', has a pointed stud, b, projecting therefrom, which rests in a socket, c, formed in a cross-bar connecting the side arms of the head B.

From the upper socket-plate, E, rises a block, F, having a conical socket, d, in its upper end.

A set-screw, e, held by a jam-nut, e', turns through an upper cross-bar, f, of the head B, and has a conical point, which enters the socket d. By adjusting the screw e all wear in the

joint can be taken up. In this manner the back bars and fork-standards are pivotally connected.

G is the seat-arm, made preferably of malleable cast-iron, as are the other metallic parts of the velocipede. To the rear end of this arm is secured the stuffed or cushioned seat H. The forward end of the arm G is forked, and is constructed to form two upwardly-turned hooks, g, which engage with horizontal studs h projecting from the sides of the block F.

At or near its center there extends downwardly through the arm G a single bolt, I, which passes through the plate E between the back bars, D, and screws into a nut, i, on the under side of such plate E. This nut is held in position and prevented from turning by projections k cast on the plate E, which projections are hammered and bent upon the nut.

Between the arm G and plate E there is placed upon the bolt I a rubber or metal spring, K, which gives elasticity to the seat-arm and seat.

In attaching the seat-arm to the velocipede it is only necessary to hook its forward end with the studs h and turn the bolt I through the arm and spring into its nut. The seat-arm can be detached with equal facility by simply removing the bolt I.

The bolt I, in addition to securing the parts, limits the expansion of the spring and the upward movement of the seat. This spring-seat, it will be seen, while having the necessary elasticity, is strong, cheap, and can be readily applied. It also has the advantage that the spring can be easily replaced, when worn out, at small expense.

My spring-seat can be used on bicycles as well as on velocipedes with three or more wheels, and can be applied to tricycles of different construction from that shown and described.

What I claim as my invention is—

1. In a velocipede, the rigid seat-arm G, pivoted at its forward end to the back of the velocipede and extending rearwardly wholly above said back, in combination with the vertical spring K, placed between such rigid seat-arm and the velocipede-back, and the vertical

bolt I, passing through said arm and spring into said back, such bolt holding the rigid seat-arm and the spring in place laterally as well as vertically, substantially as described and shown.

2. In a velocipede, the seat-arm G, having a forked forward end, constructed with hooks g, which engage with studs h on the block F, in combination with the spring K and bolt I, substantially as described and shown.

3. In a velocipede, the combination, with the seat-arm G, pivoted at its forward end, of the spring K, the bolt I, and the nut i, held by projections k on the under side of the plate E, substantially as described and shown.

OTTO UNZICKER.
